US00D812160S

(12) **United States Design Patent** (10) **Patent No.:** **US D812,160 S**
Dennis et al. (45) **Date of Patent:** **** Mar. 6, 2018**

(54) **HINGED RESISTANCE EXERCISE DEVICE**

(71) Applicants: **Douglas S. Dennis**, Loveland, OH (US); **David W. Frey**, Loveland, OH (US)

(72) Inventors: **Douglas S. Dennis**, Loveland, OH (US); **David W. Frey**, Loveland, OH (US)

(**) Term: **15 Years**

(21) Appl. No.: **29/542,277**

(22) Filed: **Oct. 13, 2015**

Related U.S. Application Data

(63) Continuation of application No. 13/354,306, filed on Jan. 19, 2012, now Pat. No. 9,248,332.

(57) **CLAIM**

We claim the ornamental design for the hinged resistance exercise device, as shown and described.

DESCRIPTION

FIG. 1 is a front perspective view of a hinged resistance exercise device showing our new design;

FIG. 2 is a front view of the hinged resistance exercise device; and,

FIG. 3 is a cross-sectional view taken along line 3-3 of FIG. 2 of the hinged resistance exercise device.

1 Claim, 2 Drawing Sheets
